EXPANSION JOINT FILLER, SHEAR BAR,
AND SLEEVE ALIGNMENT DEVICE

Robert E. Mitchell, Seattle, Wash.

Application April 2, 1934, Serial No. 718,696

4 Claims. (Cl. 94—51)

My present invention relates to that art of devices employed to facilitate the production of highways and more particularly to an expansion joint filler, shear bar and sleeve alignment device.

My present invention is for use in the construction of highways where expansion joints are used. Highways are normally made either of the so called slab construction or they are poured as a more or less monolithic highway, which, to take care of expansion due to temperature changes are provided at intervals with expansion joints. In either of the two types of construction it is desirable to fill the joint between abutting slabs or abutting strips of pavement with an expansion joint which normally takes the form of a felted strip which is impregnated with usually some bituminous product that will soften when exposed to a rise in temperature and will thus permit the compression of the joint yet when the temperature falls the matted material will return to its usual position. The placing of these strips during the construction of the highway is a matter that has required the expenditure of a good deal of construction time. It is the purpose of my present invention to provide means for holding these strips securely in position so that the fluid road materials when laid will not disarrange the same.

In order to provide that the abutting slabs or abutting strips of pavement will not be displaced vertically one from the other it has been customary to employ metal shear bars imbedded half in each abutting strip and further to insure the proper workability of the bars as the two abutting strips expand toward or away from each other, it has been customary to enclose the bar portion in one of the abutting road strips in a tube so that the bar itself will bond only with one of the abutting strips and be free to move in the other. These shear bars to be of real value must be of considerable length otherwise undue strain would occur at the margin of the slab and possibly cause breakage at that point. It has been found however that the relatively long dowels are difficult to maintain in their proper position during the pouring of the concrete. It must be realized that the concrete is fluid to a degree when poured, has considerable weight and the tamping of the same all tend to dislodge the bars. Naturally, if the dowel pins are not parallel to the longitudinal axis of movement they will cause interlocking much on the same plan as drift bolting or toe nailing. This would entirely defeat the purpose of having a free moving joint, so it is very essential

that the bars are held securely in their proper position until the road making material has been put in place, tamped and finished. One method employed in the past was to securely tie the members by wiring to support members, usually of steel, one on each side of the expansion joint filler, and then when the joint was finished to leave the support bars imbedded in the pavement. This method served the purpose intended but requires the additional use of steel and the expenditure of an unusual amount of labor all of which added to the cost of the highway and still placed the responsibility for the accurate alignment of the shear bars upon the care exercised by a workman. My present equipment serves these various purposes in an economical manner and assures accurate placement and alignment of the expansion joint material itself and of the shear bars and bar tubes used. It is intended that before the concrete has finally set but after the joint is complete otherwise my device is lifted bodily off the joint thus insuring the accurate placement of the units involved.

Other and more specific objects will be apparent from the following description taken in connection with the accompanying drawings, wherein

Figure 1 shows in perspective a complete device made after the teachings of my invention. Figure 2 illustrates in vertical section the manner of using my device. Figure 3 illustrates an adjustable end for use with my device. Figure 4 illustrates a modified form of shear bar centering arm. Figure 5 illustrates an adjustable alignment arm, this type would be substituted for each of the centering devices illustrated in Figure 1 if it is desirable to have a centering device that will be usable on pavements of varying thickness. Figure 6 is a top plan view of a complete device. Figure 7 is an elevation showing the side retaining members of a highway in section. Figure 8 is an enlarged fragmentary elevation showing in greater detail one of the shear bar securing clips or dogs.

Referring to the drawings, throughout which like reference characters indicate like parts, 10 designates the main cross bar which serves as the expansion joint holder proper. For this purpose I have found it most convenient to use an unequal leg angle having the shorter angle disposed horizontally as 11 and the longer leg as 12 disposed vertically. If angle bars are used for this purpose the so called ship bars are most desirable in that the two sides of the downwardly extending portion 12 should be parallel. For this

reason it is sometimes desirable to use steel plates broken to form the angle illustrated. The downwardly extending skirt portion 12 is notched as at 14 to provide a plurality of openings which will not interfere with the positioning of the shear bars 16. Secured to bar 10 is a plurality of alignment arms 18. The method of securing these bars to cross member 10 will vary with the expected use of the equipment. If a long stretch 10 of uniform pavement is to be constructed it would probably be desirable to rivet the alignment bars to the cross bar. For most uses however, it will be found most desirable to bolt them in place so that the spacing of the alignment bars can be 15 made to agree with the spacing of the shear bars wanted.

The exact construction of the alignment arms may be as shown in Figure 1 or it may take the form shown in Figures 4 or 5. In Figure 1 the alignment arms are shown with oppositely extending ends which terminate in downwardly extending bar centering saddle members 20 and 21. These are notched at their lower extremity as at 22 to accommodate the exact size of shear bar 23 on one side and the size of the shear bar sleeve if the same is used on the opposite side. The fit should be fairly close, to the end that the alignment bar is responsible for the accurate direction, both vertically and horizontally, given 30 the shear bars. If the device is going to be used on pavements of varying thickness then it is desirable to provide the alignment bars with adjustable end members or saddles as indicated in Figure 5. Here the construction is substantially 35 the same as the simpler form excepting the downwardly extending portions 20 and 21 are provided with rivets or bolts 24 and 25 respectively which engage the slotted saddle members 26. Then when the adjustment is secured the bolt 25 is tightened and the shear bar will be accurately positioned for depth.

In using my equipment the expansion joint strip 28 is pierced for the shear bars 16 and an expansion joint cap 30 is employed so as to insure the upper surface of the strip 28 being at the desired height with reference to the finished roadway illustrated in Figure 2 by the abutting strip 32 and 33. For cap 30 I provide the normally used U-shaped bar 30 as illustrated in Figure 2 which may be adjustably positioned by means of bolt 34 which should be threaded into bar 10 or arranged for a shim to be placed underneath the same. In either event the nut 35 secures the height adjustment. In order to center my device I provide a plurality of lugs 36 welded to cross bars 10 at intervals and spaced sufficiently from the apron portion 12 to easily accommodate the width of the joint cap 30. It is desirable to assemble an expansion strip together 60 with its appropriate shear bars and shear sleeves off the job and then put it in place as a unit. To this end it is desirable to provide means for holding strip 28 in contact with the adjusting screws 34. This I have provided in my present illustration by the pivoted dog 38 which has an upward extension as 40 permitting its manual operation and at its lower end is provided with a hook portion 41 to engage the shear bars from the underside, and thus insure holding strip 28 in intimate contact with the stops 34.

To provide handling and stabilizing facilities for my device I prefer to have end plates as 42 and 43 secured to cross bar 10. These for convenience should have considerable overall length 75 in the direction of the roadway so that when

they rest upon the side retaining members 44 they will hold my device upright. As a matter of convenience handles 46 are provided. In certain cases it is desirable to place the expansion strip 28 so as to take care of a curb which may be built as a unit with the street pavement. When this condition arises I provide slots 47 and 48 which will permit the curb portions of strips 28 as 50 and 51 to extend thru said slot.

Now it should be remembered that as the road-making material is poured it is semi-fluid and places considerable strain particularly at the time of pouring upon my device and it is essential that the same be not displaced or bowed. To prevent this I provide a plurality of spike holes as 52 and 53 so that the device may be secured by spikes to the side members 44 and then further provide a plurality of loops 54 which are fixedly secured to bar 10. Stakes are then driven down thru these loops and prevent any displacement of the bar 20 itself. Some of these loops as 56 may be of considerable length so that a bar driven down thru them will prevent canting of my device.

As most pavement is constructed so that the upper margin of a cross section is a straight line, I have indicated my device as being straight. If however a crowned road were to be constructed in a single width, the cross member 10 would of necessity have to conform to the road contour.

It has been found desirable to provide my device so that it may be adjustable for length. This is to accommodate it to roads of different width and to further take care of the increased width of roads on curves. To accomplish this I have provided the cross bar extension 60, probably best 35 illustrated in Figure 3, and in greater detail in Figures 6, 7, and 8. The bar extension is formed after the manner of bar 10 having the downwardly extending notched skirt 12 and the horizontally disposed portion 11. To secure it to cross bar 10 I have provided the spaced openings as at 62 so as to adjustably engage a plurality of lugs 64 disposed on one end of cross bar 10. When the openings 62 are matched up with corresponding lugs 64 they are secured in place by a 45 plurality of wedges 66 which in turn are secured in position by being wire bound as illustrated at 68. For use with this extended portion the aligning bars should be provided with slots as 70, referring now to Figure 4, so that they too will fit over lugs 64 after the manner probably best 50 illustrated in Figure 8.

The foregoing description and the accompanying drawings are believed to clearly disclose a preferred embodiment of my invention but it will be understood that this disclosure is merely illustrative and that such changes in the invention may be made as are fairly within the scope and spirit of the following claims.

Having thus fully described my invention, what I claim as new and desire to secure by Letters Patent is:—

1. The combination with a main supporting angle bar having a depending, notched, flange, of a series of transversely arranged centering plates 65 mounted on the bar, said plates having depending notched end-flanges alined with notches of the bar-flange to receive dowel-pins, detachable hooks pivoted on the bar for detachable engagement with the dowel-pin for holding the latter in engagement with a notch of the bar and notches of the complementary plate, and a releasing lever rigid with said hook.

2. The combination with a main supporting angle bar, an end-extension for the bar, and 75

- means for fastening said extension to the bar, of a series of transversely arranged, spaced, centering members mounted on said main bar and the end-extension, means on said centering members 5 adapted to receive and aline dowel-pins, and detachable retaining means mounted on the bar for coaction with the pins to hold the latter in engagement with the means on the centering members.
- 10 3. The combination with a main supporting angle bar having a series of spaced loops thereon, of a series of transversely arranged centering plates mounted on the bar, an end-extension mounted on the bar and provided with slots to 15 fit over said loops, some of said plates also having slots to fit over loops, and wedges engaged in said loops for retaining the plates and extension in rigid relation to the bar.
4. The combination with a main supporting angle bar and a transversely arranged centering member for a dowel-pin, of an expansion cap 5 adapted to engage a joint strip, means for attaching the centering member to said bar, said dowel-pin passing through a hole in the joint strip and engaging opposite ends of the centering member, said cap located between the main bar and the top edge of the joint strip, and an adjusting screw in the main bar for co-action with said cap.
